CLAIM

The ornamental design for a key holder, as shown and described.

DESCRIPTION

The claimed key holder is used to hold keys in readiness for their utilization. The claimed key holder can be stored in a pocket or purse when the keys are not in use.

FIG. 1 is a perspective view showing the front side and right edge thereof of a key holder having my new design;

FIG. 2 is a side view showing the front side of a key holder having my new design; and,

FIG. 3 is a side view showing the rear side of a key holder having my new design.
